UNITED STATES PATENT OFFICE.

WILLIAM GORMLEY, OF CHICAGO, ILLINOIS.

PIPE-WRENCH.

No. 813,645.

Specification of Letters Patent.

Patented Feb. 27, 1906.

Application filed December 30, 1904. Renewed August 25, 1905. Serial No. 275,848.

To all whom it may concern:

Be it known that I, WILLIAM GORMLEY, a citizen of the United States, residing at Chicago, in the county of Cook and State of Illinois, have invented new and useful Improvements in Pipe-Wrenches, of which the following is a specification.

This invention is an improved pipe-wrench in which the handle has a jaw and carries a chain arranged to be placed around the pipe and hold the same so that the jaw will take hold. It is characterized particularly by improvements with respect to the means for adjusting the chain, inasmuch as it frequently happens that a difference of one link will make the chain either too long or too short, and supplemental devices are necessary to produce the result.

In the accompanying drawings, Figure 1 is a side view of the wrench. Fig. 2 is an edge view. Fig. 3 is a section on the line 3 3 of Fig. 1. Fig. 4 is a detail in perspective of an adjusting-wedge.

Referring specifically to the drawings, 6 indicates the handle, which is squared at the lower end, as at 7. The jaws 8 are secured to the front end of the handle by bolts 9, there being a jaw on each side of the handle. The jaws are double—that is, they are toothed on both sides, so that the pipe may be gripped on either side thereof. This construction is advantageous, because when one side wears out the other side can be used. The attachment of separate jaws by bolts is advantageous, because should a jaw break it can be renewed without the expense of a whole wrench.

Upon the squared portion of the handle above the jaws is a sleeve 10, having on one side an eye 11, in which the chain 12 is connected, and having on the other side forks 13, which receive any link of the chain and hold the same. The chain may thus be adjusted to accommodate pipes of different sizes.

To permit a nicer adjustment than is permitted by the means above referred to, the sleeve 10 is loose on the shank 7 and may be moved up and down and held at adjustment by a pin 14, which fits through a hole in the side of the sleeve and into any one of a series of holes 15 in the shank.

A further means of adjustment is provided by a wedge 16, which is forked to fit around the shank 7. This wedge may be inserted between the collar 10 and the top of the jaws 8 to vary the distance of said collar and accordingly the length of the chain. The wedge is conveniently connected by a chain 17 to the head of the pin 14, so that it can be used or hang free, as desired.

What I claim as new, and desire to secure by Letters Patent, is—

In a wrench, the combination with a handle, having jaws at the end thereof, of a sleeve 65 slideable on the handle, an adjusting-wedge insertible between the jaws and the sleeve, and a chain attached at both ends to the sleeve.

In testimony whereof I have signed my name to this specification in the presence of two subscribing witnesses.

WILLIAM GORMLEY.
